UNITED STATES PATENT OFFICE.

JAMES C. POTTER, OF LOWELL, MASSACHUSETTS.

EVENING MECHANISM FOR COTTON-OPENERS.

SPECIFICATION forming part of Letters Patent No. 375,301, dated December 20, 1887.

Application filed July 6, 1887. Serial No. 243,507. (No model.)

To all whom it may concern:

Be it known that I, JAMES C. POTTER, of Lowell, in the county of Middlesex and State of Massachusetts, have invented certain new and useful Improvements in Evening Mechanisms for Cotton-Openers and other Engines or Machines for Working Cotton and other Fibrous Materials, of which the following is a specification.

10 My invention has relation to that kind of evening mechanism which comprises, among other things, an evener-roll and pivoted or hinged evener-plates co-operating therewith, in combination with scale-levers and means 15 whereby the movements of said scale-levers (due to that of any one or more of the evener-plates) are availed of to shift the belt on the cone pulleys or drums for the purpose of regulating the feed. Heretofore, so far as I am 20 informed, it has been customary in evening mechanism of this kind to arrange the scale-levers one above the other in a vertical plane, connecting the uppermost scale-levers with their appropriate evener-plates by rods ex- 25 tending between said levers and plates, and supporting the lowermost or main scale-lever upon the shorter arm of a pivoted vibratory weighted lever, which acts to hold up the connecting-rods against the evener-plates, and at 30 the same time serves to actuate the cone-belt shipper. Such an organization as the one just referred to is illustrated in Letters Patent No. 146,794, of January 27, 1874, among others. One drawback to said arrangement is that, as 35 the end of the vibratory weighted lever moves in the arc of a circle, the point at which it meets the main-scale lever will, when the said scale-lever moves, be carried to one side or the other of the vertical plane of the scale- 40 levers, with the effect of canting said levers out of plumb, and thus cramping their movement, rendering them less sensitive and requiring greater power to actuate them. In the instance just referred to the weighted or 45 fulcrum lever is arranged to vibrate in a plane transverse to that of the scale-lever system; but a similar disadvantage results when the said lever vibrates in a plane parallel to or coincident with that of the scale-lever system, 50 as is sometimes the case. The end of the fulcrum-lever still moves in a curved path, and

the tendency of this movement is to pull the scale-lever system endwise in one direction or the other, according to the direction of vibratory movement of the end of the fulcrum-lever. 55 Thus so long as the end of the fulcrum-lever vibrates or moves in a curved path the tendency will be to disturb the scale-lever system, with the effect of cramping and rendering less sensitive the same. Another drawback is due 60 to the fact that the connecting-rods meet the plates themselves, which have in any event a comparatively slight range of movement, the consequence being that a correspondingly slight movement is imparted to the scale-levers 65 themselves, so that the exaggeration of this movement necessary for the successful operation of the belt - shipper must be effected through the instrumentality of the mechanism intermediate between the scale-levers and the 70 shipper. Still another drawback is that the evening mechanism under this arrangement has been placed beneath the machine in a position where it is liable to catch and be clogged by lint and other refuse. It has been my ob- 75 ject in the present invention to obviate these and other minor disadvantages, which will hereinafter be referred to.

To this end I substitute for the vibratory weighted lever a weighted slide, upon the end 80 of which the main scale-lever is fulcrumed, said slide being movable back and forth in a right line in the plane of the scale-lever system, whether the latter be in a vertical or a horizontal plane. I prefer, however, to ar- 85 range the scale-levers in a horizontal plane, all of them resting upon a horizontal floor or plate, which is covered or boxed over, both to protect the scale-lever system from lint, &c., and also to prevent them from rising or get- 90 ting out of line. The scale-lever system is also placed back from under the evener-plates and feed - rolls. The weighted slide, like the weighted lever, acts not only to cause the connecting-rods of the scale-lever system to hold 95 the evener-plates up in place, but also to communicate movement to the cone-belt shipper; and to this end I prefer to mount said shipper upon a slide capable of movement in a right line parallel with the axis of the two cone- 100 drums, communicating movement to said shipper-slide from the weighted slide by rack-and-

pinion or other suitable known instrumentality.

Instead of applying the scale-lever-connecting rods to the evener-plates themselves, I form each evener-plate as an angle or elbow lever, pivoted, at their elbows upon a common fulcrum-rod, and having their vertical and longer arms connected at their ends to the scale-lever-connecting rods, which, like the scale-levers themselves, are placed horizontal instead of vertical. In this way a comparatively slight movement of the shorter arm of the angle-lever, which constitutes the evener-plate proper, will impart a greater range of movement to the outer end of the longer arm to which the scale-lever-connecting rod is jointed, thus giving more movement to that rod than it would have were it acted on directly by the evener-plate.

20 The nature of my improvements and the manner in which the same are or may be carried into effect will be readily understood by reference to the accompanying drawings, in which—

25 Figure 1 is a plan view of so much of a cotton opener or lapper as is needed to explain my invention. In this figure the feed-apron and frame therefor are removed and the scale-lever box is open. Fig. 2 is a side elevation 30 of the same, with a portion of the frame broken away to expose the scale-lever system and its accessories. Fig. 3 is a front elevation of the same. Fig. 4 is a side elevation, on enlarged scale, of the evening mechanism. Fig. 35 5 represents in elevation and plan the arrangement for transmitting motion from the weighted slide to the ordinary quadrant belt-shipper levers which are employed when the cone-drums are vertical (which has heretofore 40 been their customary arrangement) instead of horizontal, as they are represented in the preceding figures.

A is the frame of the machine.

B is the beater.

45 E F are the two feed rolls.

H is the evener-roll.

J is the rod on which the evener-plates are fulcrumed.

K are the evener-plates, formed as angle or 50 elbow levers, having their longer and vertical arms, K', pinned at their lower ends, each to its appropriate horizontal scale-lever-connecting rod L.

M are the scale-levers, resting upon the horizontal floor or plate N, which forms the bottom of a box, the flanged cover of which is represented at O. The connecting-rods, as usual, have pointed ends to enter cups or sockets formed for them in the ends of the 60 scale-levers, and they pass to the arms K' through openings in the front of the scale-lever box, which are slightly enlarged, so as to allow them the freedom of movement made necessary by the fact that they are jointed or 65 pinned to the arms K'. The scale-lever box is supported by brackets attached to the vertical cross-partition C, which shuts off from

the working parts of the opener those parts of the evening mechanism which are most likely to be clogged by lint and refuse.

To the under side of the scale-lever box is fixed a plate, D, which at the front of the box rises in the form of a bracket, D', to furnish bearings in which the rod G is mounted and can slide back and forth, a head, G', on said rod serving to limit the extent of its forward movement (should it be necessary) and also as a handle to manipulate it. This rod, which is the instrumentality hereinbefore referred to as the weighted slide, enters at its front end through the front of the scale-lever box and bears at its point against the fulcrum-point of the main scale-lever, as indicated plainly in Fig. 1. In the plate D is cut a dovetailed way, in which is mounted the slide-bar H², 80 having at its front a vertical arm, H', which is secured (preferably adjustably secured, as hereinafter described) to the rod G. On the under side of bar H² is a rack, a, which engages gear b, fast on shaft I, which has its bearings in hangers secured to the under side of the scale lever box. On this shaft is an arm or segment-pulley, c, from which hangs a weight, d, so placed as to tend to revolve the shaft I in a direction to move the rack-bar H², 90 and consequently the slide G, toward the scale-levers. In this way the slide G is weighted and is caused to bear with yielding pressure against the main scale-lever.

For the purpose of varying the normal feed of the machine I prefer to adjustably connect the rack-bar H² to the slide-rod G, to which end the arm H' of the bar through which the rod passes is internally screw-threaded and is engaged by a corresponding screw-thread 100 upon the exterior of the rod. By revolving the rod by means of its handle or head G' the rack-bar H can be advanced or retracted, thus moving the mechanism (hereinafter described) intermediate between it and the cone-belt to 105 a position to bring said belt to the desired position upon the cone-drums.

The intermediate mechanism referred to can best be seen by reference to Figs. 3 and 4. Upon the end of shaft I, which projects beyond and to the left of the frame of the machine in Fig. 3, is fixed a segment-gear, e, which engages a corresponding gear, f, mounted upon a stud, g, on the side of the frame. Upon the hub of gear f is fixed the large toothed sector h, and this sector engages and operates the horizontal sliding rack-bar P, mounted in guides h' on the frame of the machine in such manner that it will slide back and forth in a right line parallel with the axes of the upper and lower cone-drums, R S, which are placed horizontal, with their axes parallel to each other. To the sliding rack-bar P is rigidly fixed the shipper i, provided with forks i' to engage the cone-drum belt j. The shipper thus at all times moves in a right line and parallel with the axes of the cone-drums.

The lower cone-drum, as usual, is driven from the beater-shaft by belt 1 and pulleys 22.

From the upper cone-drum motion is imparted to the evener-roll by worm 3 and worm-wheel 4. From the evener-roll motion is imparted by gears 5 6 to the apron-roll, and by gears 7 8 to the lower one, F, of the feed-rolls.

The mechanism described by reference to Figs. 1 to 4 is that which I prefer. Its mode of operation and the resulting advantages have already been sufficiently indicated. In case, however, it should be desired to have the cone-drums vertical instead of horizontal, this can readily be provided for, as indicated, for instance, in Fig. 5. In the arrangement shown in this figure the drums are vertical and between them are the customary toothed quadrant levers, k, engaging one another and having belt-shipping forks l at their outer ends. To impart movement to these levers the shaft I would have on it a pinion, m, to engage a pinion, n, on the hub of one of the quadrants. This arrangement, however, as respects the shipper, is inferior to that illustrated in the other figures, for the reason that the shipping-forks move in the arc of a circle instead of in a right line.

Having described my improvements and the manner in which the same are or may be carried into effect, I state in conclusion that I do not restrict myself to the specific construction and arrangement of parts hereinbefore described, because manifestly the same can be varied in several respects without departure from the invention; but

What I claim herein as new and of my own invention is as follows:

1. The combination, with the scale-levers, of the weighted slide furnishing a fulcrum for the main scale-lever and arranged to move back and forth in a right line in the plane of the scale-lever system, substantially as and for the purposes hereinbefore set forth.

2. The scale-levers arranged and supported in a horizontal plane, in combination with the weighted horizontal slide furnishing a fulcrum for and bearing with yielding pressure against the main scale-lever, and arranged and adapted to move back and forth in a right line in the

plane of the scale-lever system, substantially as and for the purposes hereinbefore set forth.

3. The pivoted evener-plates formed as angle or elbow levers, in combination with the scale-levers arranged and supported in a horizontal plane, and the intermediate horizontal pressure-transmitting rods, as and for the purposes hereinbefore set forth.

4. The combination of the pivoted evener-plates formed as angle or elbow levers, the horizontally-arranged scale-levers, the connecting-rods jointed at one end to the longer and vertical arms of said elbow-levers and bearing at the other end against the scale-levers, and the weighted slide furnishing a fulcrum for the main scale-lever and movable back and forth in a right line in the plane of the scale-lever system, substantially as hereinbefore set forth.

5. The combination, with evening-plates and intermediate pressure-transmitting rods, of the scale-levers arranged in horizontal position and inclosed in a box located in the frame of the machine at a point in front of the evening-plates, substantially as and for the purposes hereinbefore set forth.

6. The weighted slide G, in combination with its supporting-bracket, and the sliding rack-bar adjustably connected to said slide, substantially as and for the purposes hereinbefore set forth.

7. The combination, with the horizontal scale-lever system and the horizontal weighted slide furnishing a bearing for the main scale-lever and arranged to move back and forth in a right line in the plane of the scale-lever system, of the cone drums and belt, the belt-shopper, and mechanism whereby said shipper is actuated from said slide at the times and in the manner substantially as hereinbefore set forth.

In testimony whereof I have hereunto set my hand this 21st day of May, 1887.

JAMES C. POTTER.
